UNITED STATES PATENT OFFICE.

PERRY A. GORDON, OF JET, OKLAHOMA TERRITORY.

SIGNAL.

No. 806,082.

Specification of Letters Patent.

Patented Nov. 28, 1905.

Application filed July 18, 1905. Serial No. 270,278.

To all whom it may concern:

Be it known that I, PERRY A. GORDON, a citizen of the United States, residing at Jet, in the county of Woods, Oklahoma Territory, have invented certain new and useful Improvements in Signals; and I do hereby declare the following to be a full, clear, and exact description of the invention, such as will enable others skilled in the art to which it appertains to make and use the same.

This invention relates to signals.

One object of the invention is to provide a simple, inexpensive, durable, and efficient device for manipulation by a mail-carrier or other person to signal at a distant point the deposit of mail in a mail-box.

Another object of the invention resides in the provision of a signaling mechanism for use in rural districts for signaling at distant points the fact that mail has been deposited in the mail-box.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the present invention.

In the drawings, Figure 1 is a side elevation of my invention, the dotted lines indicating the location of the flag in its elevated position. Fig. 2 is a vertical sectional view of the invention. Fig. 3 is a top plan view of the invention. Fig. 4 is a detail view of the latch-plate. Fig. 5 is a detail view of the spring-actuated bolt.

Referring now more particularly to the accompanying drawings, the reference character 1 designates a post having its upper portion reduced upon opposite sides, as indicated by the reference characters 2, to form shoulders 4, upon which rests the lower ends of the sides 6 and 7 of a casing 8, whose rear portion extends rearwardly of the rear side of the post 1 and is provided with an opening 9 in its bottom rearwardly of the said post for a purpose presently explained. It will be noted that the casing 8 is closed at its back by a piece 10 and at its top by a piece 11.

Secured in any suitable manner to the front face of the post 1 with its upper face 12

parallel with the horizontal plane of the aforesaid shoulders 4 is a support 13, which is held in position by means of a brace 14, whose upper end is connected to the under face of the support 13, with its opposite end secured to the inner face of the post 1 beneath said shoulders.

The front of the post 1 above the shoulders 4 has its outer face parallel with the inner edges of the sides 6 and 7 of the casing and is provided at its upper end with an opening 15, leading into the hollow portion 16 of the casing, which hollow portion extends the entire length of the post from its top to the aforesaid shoulders 4 for the sliding therein of a weight 17, connected at one end to a cord 18, which passes upwardly through the aforesaid hollow portion 16 and over a pulley-wheel 19, journaled upon the axle 20 in the aforesaid opening 15 at the upper end of the post 1, and which then passes downwardly upon the inner face of the post 1 through the guide 22, secured to the post and connected at its end with a latch-plate 23, which latter is provided with a central perforation 24 for registration with the perforation 25 in the inner face of the post 1 immediately above the aforesaid shoulders 4 and 5.

Fixedly secured upon the support 13 are guides 26 and 27 for the sliding reception of a bolt 28, which is designed to pass through the openings 24 and 25 of the latch-plate 23 and the posts, respectively, to hold the latch-plate 23 and the flag 29 in their downward position, the said bolt having a shoulder 30 near its inner end for engagement with the bracket 27 to limit its inward movement against the action of the helical spring 31, which encircles the bolt between the said shoulder 30 and the aforesaid bracket 26.

It will now be understood that the cord 18 is connected at one of its ends to the latch-plate 23 and at its opposite end to the weight 17, confined within the hollow portion 16 of the casing 8 and that the latch-plate and said weight are held in a certain position while the spring-actuated bolt 28 is in engagement with the latch-plate. Now when mail has been deposited in the mail-box (not shown) the mail-carrier or other person may grasp the knob 32 of the bolt 28 and pull the same outwardly, thereby releasing the latch-plate 23 and permitting it and its guide 17 to pass upwardly, the cord pass-

ing through the said guide 17, and the flag 29, which is secured to the said cord, will cease to move upwardly immediately upon contact with the weight 33, secured upon the said cord, with the said guide 17, the said weight 33 being secured to the cord immediately above the flag 29. The flag is thus elevated and held in its elevated position by reason of the weight in the hollow portion 16 of the casing being of such proportions as compared with the weight 33 as to prevent accidental downward movement of the flag. A person at a distant point seeing the flag in this elevated position will know that mail has been deposited in the mail-box. When it is desired to lower the flag, it is simply necessary to pull upon the cord 34, which is secured at one of its ends to the latch-plate 23 and at its opposite end to a staple 35, secured 20 to one side of the support 13 or the post 1, as may be desired, the said staple being shown as secured to the said support.

It will be understood that my invention is not connected in any manner to the mail-box, but, on the other hand, is secured to the post at any distance from the mail-box as may be desired, but preferably in close proximity thereto, and it is apparent that just as soon as the spring-actuated bolt is disengaged from the perforations of the latch-plate and the post the weight within the casing will positively cause an elevation of the flag. Of course any color of flag may be used; but in the event that several posts may of necessity be in close proximity flags of different colors may be used, so that the owners of different boxes at different points could readily determine whether or not the signal for their box had been operated, it being understood 35 that the invention is particularly desired for persons residing some distance off from the mail-route.

What is claimed is—

1. A signaling device comprising a post having an opening in its upper end, a hollow casing embracing the post with its rear portion extending rearwardly of the post to form a hollow passage between the post and the rear of the casing, a pulley-wheel mounted in the said opening in the post, a support secured to the post, a spring-actuated bolt mounted upon said support, a latch-plate, a cord attached to the latch-plate and passed over said pulley and having a weight connected to its opposite end for sliding movement in the passage between the rear of the casing and the post, the said cord having a flag secured thereto and adapted to be held in its lowered position by means of the spring-actuated bolt engaging the aforesaid latch-plate.

2. A signaling device comprising a post, having an opening in its upper ends, a support secured to the post beneath said opening, a pulley-wheel, mounted in said opening, 65 a cord passed from said pulley and secured at one of its ends to a latch-plate and at its opposite end to a weight, a flag secured to the cord, said post having a perforation therein beneath the said opening, the latch-plate having a perforation therein, and a spring-actuated bolt passed through the perforation of the latch-plate and the bolt to hold the latch-plate in its lower position whereby the latch-plate, the cord and the flag may be released 70 upon disengagement of the spring-actuated bolt from the perforations of the latch-plate and the post.

In testimony whereof I affix my signature in presence of two witnesses.

PERRY A. GORDON.
